THOMAS A. COLEMAN, OF FULLERTON, LOUISIANA, ASSIGNOR TO PETER VREDENBURGH,
JR., OF VREDENBURGH, ALABAMA.

FEED-ROLL.

1,177,931.

Specification of Letters Patent.

Patented Apr. 4, 1916.

Application filed May 11, 1914. Serial No. 837,755.

To all whom it may concern:

Be it known that I, THOMAS A. COLEMAN, a citizen of the United States, residing at the town of Fullerton, parish of Vernon, 5 and State of Louisiana, have invented a certain new and useful Improvement in Feed-Rolls, of which the following is a full, clear, and exact description, such as will enable others skilled in the art to which it 10 appertains to make and use the same, reference being had to the accompanying drawings, forming part of this specification.

My invention relates broadly to milling machinery, and specifically to an improvement 15 in feed rolls for lumber-working machines, such as edgers.

As is generally understood, in the manufacture of lumber, the boards as sawed from the logs are in varying widths. In order to 20 secure boards of uniform width, and having squared edges, the rough lumber is run through edgers, wherein a gang of saws cut them into the selected widths, and square the edges. In order to do this properly, it 25 is necessary to have an absolutely positive and secure feed to present and hold the board properly to the operation of the saws.

The customary feeding mechanism comprises one or more feed rolls which have 30 irregular surfaces so as to engage the board and feed it forward, and suitable press rolls which hold the board securely in engagement with the feed rolls. Inasmuch as the machines must be quite wide, in order to accom- 35 modate boards of maximum widths usually cut from the logs, it follows that the feed rolls must be of considerable length.

The feed rolls necessarily are subject to hard usage which frequently causes break- 40 age of the teeth, fluting or other surface formation by virtue of which the feed roll has working engagement with the boards. When a feed roll becomes thus mutilated, it 45 renders the machine inaccurate, and must either be repaired or replaced.

The principal purpose of my invention is to provide a construction of feed roll which will be very strong and very economical.

More specifically, the object of my invention 50 consists in providing a construction of feed roll wherein the working surface is made up of a plurality of individual removable elements having suitable form to provide means for engaging the boards. By virtue of this construction, when any one of

said elements is broken or mutilated, it may be withdrawn and replaced without necessitating replacement of the entire feed roll or difficult and expensive repairs.

A further object of my invention is to provide a construction wherein the engaging elements of a feed roll may be selectively arranged so as to vary the extent of the working surface of the roll, or to provide intervals along the length of the roll which are devoid of engaging elements.

With these and other objects in view, which will hereinafter be made apparent, it will be understood by reference to the accompanying drawings, that—

Figure 1 illustrates a longitudinal sectional view of a portion of a feed roll containing my improvements. Fig. 2 illustrates a cross section of the same, taken substantially on line 2—2 of Fig. 1. Fig. 3 illustrates a modified form of clamping ring. Fig. 4 illustrates a modified form of barrel. Fig. 5 is a side view partly broken away of a modified form. Fig. 6 is an illustration of 80 the same with the engaging elements in place. Fig. 7 is an end view of one of the barrels illustrated in Figs. 5 and 6.

Referring to the drawings more specifically, the numeral 1 designates a shaft which is continuous throughout the length of the feed roll, being suitably supported in journals and provided with driving mechanism whereby it may be rotated. Shaft 1 is provided with one or more continuous longitudinal splines 2 formed on the shaft. Slidable longitudinally on the shaft, and held against rotation relative thereto by the splines 2, is a clamping collar 4, and a clamping nut 5, or other suitable means is provided for moving the collar 4 inwardly on the shaft and preventing its movement backward.

Mounted on the shaft, and held against rotation thereon by the splines 2, is a series 100 of drums or barrels 6 which support between them clamping rings 7. These rings are triangular in cross section, having the inwardly sloping faces 7^a. The ends of the barrels 6 are beveled off to form the shoulders 6^a which engage under the sloping faces of the rings and a similar sloping face 4^a of the clamping collar 4. As will best be understood by reference to Fig. 2, the barrels 6 are provided with longitudinal slots 8 extending from end to end of the barrels, and adapted to receive the engaging elements 9.

The engaging elements 9 are suitable strips of hard metal which are formed with the saw teeth 10, or otherwise suitably knurled or formed, so as to secure a working engagement with the material to be handled by the roll. The ends of the engaging elements 9 are mitered off so as to conform to the beveled portion 6^a of the barrels, and so that they will engage under 10 the inwardly sloping faces of the clamping rings and the clamping collar.

The barrels 6 are slideable longitudinally on the shaft 1, and are adapted to be clamped in position against the clamping rings 7 by 15 means of the clamping collar 4 and a similar clamping collar at the other end of the shaft, which are moved inwardly to effect the clamping operation by screwing up the clamping nuts 5. Or if desired, one of the 20 end collars may be shrunk on the shaft and the clamping operation effected by inward movement of the other collar.

As will be plainly understood, the engaging elements 9 are placed in the slots in the 25 barrels 6 and the barrels and clamping rings 7 clamped together by the collars 4, whereby the engaging elements 9 are securely held in position by virtue of their engagement under the sloping faces of the rings and 30 collars.

In case of injury to any of the clamping elements 9, the roll can be repaired quickly by simply loosening the nut 5, sliding back 35 the collar 4, and sliding back the barrels 6 until the ends of the injured engaging elements are disengaged from under the rings 7. Thereupon the injured member can be 40 removed and replaced, and the roll quickly reassembled by moving the portions together and clamping them in position, as above described. This construction, therefore, renders it unnecessary to remove any of the barrels or collars from the shaft, or the shaft 45 from its bearings. In case it is desired to have a portion of the roll bare of the engaging elements, they can be removed from such of the barrels as desired, leaving intervals wherein the roll does not carry engaging 50 elements.

50 In Figs. 3 and 4, I have illustrated a modified form of clamping ring and barrel. Instead of being triangular in cross section throughout its circumference, the ring illustrated in Fig. 3 is quadrilateral in cross section and has seats 10 milled in both sides, which seats are adapted to receive the projecting ends of the engaging elements 9. For this type of ring, the ends of the barrel 55 instead of being beveled, are shouldered so as to provide the shoulder 11 which fits within the ring and against its inner periphery.

It will be observed that the clamping rings are not restricted by the shaft against movement transversely thereof, and hence they 65 will be self-centering between the juxtaposed carriers, and consequently will equalize the pressure on all of the engaging elements about the periphery of the carriers. This insures all the engaging elements being 70 securely clamped in place.

The barrels 6 may be of any desired length, and therefore, any desired number to a roll, and, of course, the length of the engaging elements 9 is governed by the 75 length of the barrel.

From the foregoing, it will be apparent that my improved feed roll is made up of a plurality of individually mounted carriers and interposed clamping members which 80 cooperate to support and clamp the engaging elements in position, said several members being individually movable so as to permit the removal and insertion of individual engaging elements. 85

I am aware that this device is adapted to a variety of applications, and that various changes and modifications therein may be made whereby to adapt it to different specific uses. Therefore, it is not my intention 90 that my invention be limited to the specific forms illustrated and described.

What I claim is:

1. A sectional feed roll comprising a shaft, a plurality of carriers mounted thereon, engaging elements removably mounted in the carriers, clamping members having an inwardly decreasing cross section disposed between the carriers for engagement with the ends of the engaging elements, said 95 clamping members being so constructed that they are centered by engagement with the engaging elements, and means for securing the engaging elements and clamping members in contact. 100

2. A sectional feed roll comprising a shaft, a pair of relatively movable carriers supported on the shaft, engaging elements removably mounted in the carriers and extending longitudinally of the shaft, a clamping member having its opposite sides beveled and converging toward the shaft, said 110 clamping member being angularly movable relative to the shaft so as to have equalizing engagement with the engaging elements, and means for securing the engaging elements and clamping member in contact. 115

In testimony whereof I hereunto affix my signature in the presence of two witnesses, this 5th day of May, 1914.

THOMAS A. COLEMAN.
